UNITED STATES PATENT OFFICE.

WILFORD JUDSON HAWKINS, OF MONTCLAIR, NEW JERSEY, ASSIGNOR TO AMERICAN MACHINE & FOUNDRY COMPANY, A CORPORATION OF NEW JERSEY.

PRESSURE-CHAMBER AND PLUNGER CONSTRUCTION.

Application filed August 21, 1923. Serial No. 658,517.

To all whom it may concern:

Be it known that I, WILFORD JUDSON HAWKINS, a citizen of the United States, residing at 89 Undercliff Road, Montclair, 5 in the county of Essex and State of New Jersey, have invented certain new and useful Improvements in Pressure-Chamber and Plunger Constructions, of which the following is a specification, reference being had 10 therein to the accompanying drawing.

This invention relates to a pressure chamber and plunger construction, wherein the plunger is adapted to act on a pressure fluid within the chamber, and the invention is 15 designed with special reference to the employment of such unit in a suspension device for connecting an elevator car or the like to its housing cables, in order to equalize the loads and stresses on the cables; and 20 the invention consists of an improved form of pressure chamber and plunger construction, in which the plunger slides fluid-tight within the pressure chamber and around a sleeve extending into the chamber and sealing 25 the same against the escape of the pressure-fluid, a rod being extended within the sleeve and engaged with the plunger; whereby the provision of a stuffing-box at the end of the chamber where the rod passes therethrough is avoided.

The invention is shown as embodied in a plurality of such units for the attachment of an elevator car or the like to its housing cables, wherein a casing adapted for attachment to the car is provided with a plurality of pressure chambers communicating with each other, and sleeves are extended into the respective chambers and seal the same at one end against the escape of pressure-fluid, a 35 series of plungers being provided which fit slidingly within the respective chambers and around the respective sleeves, and rods being extended within the sleeves and engaged with the plungers and adapted to be connected with the housing cables; whereby the 40 pressure-fluid in the chambers will be caused by the pressure of the plungers to flow from one chamber to another, and will thereby distribute the weight of the car among the several plungers, with the result that the loads and stresses on the cables will be 45 equalized.

The invention consists also, in employing as a pressure-fluid medium, in pressure

chamber and plunger constructions, a material which does not become fluid and run at temperatures below say 95° F. or thereabout. Paraffin is one example of such material, and under the influence of the pressure exerted by the plunger thereon, will be 60 caused to flow.

The invention consists also in the details of construction and combination of parts hereinafter described in the claims.

In the accompanying drawings:

Fig. 1 is a view in vertical section on the line 1—1 of Fig. 2 of a plurality of pressure chamber and plunger units adapted to serve as a suspension device for connecting an elevator car or the like to its suspension cables 70 to equalize the load.

Fig. 2 is a horizontal section on the line 2—2 of Fig. 1.

Fig. 3 is an elevation showing an elevator connected with the suspension cables by the 75 device shown in the preceding figures.

Referring to the drawings:

My improved pressure chamber and plunger construction of which a number are shown in cooperative relation to each other to constitute an equalizing suspension device for elevators consists of a casing 1, enclosing a pressure-fluid chamber 2, adapted to contain a suitable pressure-fluid 3. Extending downward into the chamber through the top 85 of the casing is a sleeve 4 which is fitted at its upper end in a hole in the casing top and is fastened therein in such manner as to seal the same against the escape of the pressure-fluid around the exterior of the sleeve. 90 The sleeve is open at both ends, and surrounding its lower end is a hollow annular plunger 5, which fits in the chamber and surrounds the sleeve so as to slide thereon. The lower end of the plunger projects 95 through the lower open end of the chamber and is formed with a head 5*. At its opposite end, the plunger has applied to it an annular gasket or packing 6, which fits fluid-tight within the chamber and around the sleeve, so that the escape of the pressure-fluid from the chamber between the sleeve and plunger and between the plunger and wall of the chamber is prevented. A rod 7 extends downwardly within the sleeve and out through the lower end of the same and is engaged with the head 5* of the plunger, which latter is formed with a threaded open-

ing in which the lower end of the rod is screwed and confined by holding nuts 9.

As a result of the construction described, the plunger acts with pressure on the pressure fluid when the former is moved into the chamber by the rod 7 extending through the upper end of the casing, and is cushioned by the body of confined fluid. Due to the sealing of the chamber by the sleeve, and 5 due to the fluid-tight fit of the plunger within the chamber and around the sleeve, the employment of a stuffing-box in the end of the chamber, usually employed to prevent the escape of fluid around the plunger rod, is 10 avoided. In other words, the fluid is prevented from escape from the upper end of the chamber by the sleeve, and from its opposite end by the plunger, at the same time affording the plunger rod a free passage 15 20 through the end of the casing.

Where the plunger surrounds the lower end of the sleeve and rod, an annular space 10 is formed between the exterior of the rod and interior of the plunger, in which a suitable lubricant may be placed to ensure the 25 proper lubrication of the rod where it slides through the sleeve and of the plunger where it surrounds the sleeve.

In the disposition of these units in cooperative relation to each other to connect an elevator car or the like to its hoisting cables, so as to equalize the stresses and loads on the cables, the units are arranged in two rows, in staggered relation and the chambers are covered at their upper ends by the top of the casing and are open at their lower ends. At their upper ends these chambers have free communication with each other through lateral openings 12 formed in the 30 35 40 45 50 55 60 65 walls of the chambers, through which the fluid may flow from one chamber to another, and each chamber has extending into it a sleeve 4 sealing the upper end of the chamber, on which sleeve slides a plunger 5 having connected with it a rod 7 extending through the sleeve, the whole constituting a device which is shown as connecting an elevator car A to its suspension cables B. The casing is mounted between and fastened to the cross-head channels C on the top of the car, with the cables B passing over the sheave E and connected at their lower ends, respectively, with the upper ends of the rods 7, whereby the weight of the car is supported by the pressure fluid in the chambers confined between the top of the casing and the plungers. Under these conditions, any stretching or contraction of the cables, resulting in the change of length of the individual cables, which would otherwise place unequal stresses on the same, and which might be so pronounced as to cause the cables to part or be seriously injured, will be compensated for by the action of the 70 75 80 85 90 95 100 105 110 115 120 125 130 plungers on the common body of pressure-

fluid, which in flowing from one chamber to another will cause the weight of the car to be equally distributed among the several plungers, without regard to the position of the plungers in their respective chambers. 70 In other words, the plungers being movable independently of each other in their chambers, and the connected cables being independently adjustable by such movements relative to the supporting sheave and car, 75 the effect will be to bring about an equalization of the stresses on the cables and any variation in the loads imposed thereon. While different kinds of pressure-fluids may be employed to fill the pressure chambers, I 80 prefer to use a material, such as paraffin, which does not become fluid and run at temperatures, say below 95° F. or thereabout. Such a pressure-fluid will, under the degree of pressure to which it is subjected by the 85 action of the plungers in sustaining the weight of the car, become fluid and flow from one chamber to another in distributing the load imposed uniformly among the several plungers and cables. 90

While in the accompanying drawings I have shown my invention employed in the particular detailed form which I prefer to adopt, it will be understood that these details may be variously changed and modified without departing from the limits of the invention. And while I have shown the device employed in connection with an elevator, it will be understood that it may be employed in other connections; and the single unit of construction of Fig. 1 is capable of various uses, especially as a cushioning means for relatively movable parts, as a dash-pot, or the like. 100

Having thus described my invention, 105 what I claim is:

1. In a mechanism of the type described, the combination with a casing having a pressure-fluid chamber therein, of a sleeve extending into the casing and sealing the same at one end against the escape of the pressure-fluid, a plunger surrounding the sleeve and sliding in the chamber, and a rod extending within the sleeve and engaged with the plunger. 110

2. In a mechanism of the type described, the combination with a casing having a pressure-fluid chamber therein, of a sleeve extending into said chamber and sealing one end of the same against the escape of the pressure-fluid, a plunger fitting fluid-tight within the chamber and around the sleeve, and a rod extending within the sleeve and engaged with the plunger. 120

3. In combination with a casing having a pressure-fluid chamber therein, a sleeve fixed to the casing at one end of the chamber and extending into the chamber and sealing the same against the escape of the pressure-fluid at one end, a plunger fitting 125 130

fluid-tight within the chamber and around the sleeve, and a rod extending within the sleeve and engaged with the plunger.

4. In combination with a casing having a pressure-fluid chamber therein, a sleeve extending within said chamber and sealing one end of the same against the escape of the pressure-fluid, a plunger fitting fluid-tight within the chamber and around the sleeve, and a rod extending within the sleeve and engaged with the plunger and adjustable longitudinally relatively thereto.

5. In combination with a casing having a pressure-fluid chamber therein, a sleeve extending within the chamber and sealing one end of the same against escape of the pressure-fluid, an annular plunger within the chamber and surrounding the sleeve, a packing applied to one end of the plunger and engaging the sleeve and wall of the chamber to seal the same against the escape of the pressure-fluid, and a rod extending within the sleeve and engaged with the opposite end of the plunger.

25 6. In combination with a casing having a pressure-fluid chamber therein, a sleeve extending into the chamber and sealing one end of the same against the escape of the pressure-fluid, a hollow annular plunger within the chamber and surrounding the sleeve, a packing at one end of the plunger fitting said parts fluid-tight, said plunger being provided at its opposite end with a head, and a rod extending within the sleeve and engaged with said head.

7. In a mechanism of the type described, the combination with a casing having a pressure-fluid chamber therein, of a sleeve extending into the chamber and sealing the same at one end against the escape of the pressure-fluid, a hollow plunger surrounding the free end of the sleeve within the chamber and slideable on the sleeve and extending beyond the end of the same, said plunger being closed at its end to form a lubricant-holding chamber between the interior of the plunger and the exterior of the sleeve, and a rod extending within the sleeve and engaged with the end of the plunger.

50 8. In a mechanism of the type described, the combination of a casing having a plurality of pressure-fluid chambers therein communicating with each other, sleeves extending into said chambers respectively and sealing one end of the same against the escape of the pressure-fluid, plungers fitting fluid-tight within the respective chambers and around the respective sleeves, and rods extending within the sleeves and engaged with the respective plungers.

9. In a mechanism of the type described, the combination with a casing having a plurality of pressure-fluid chambers communicating with each other at one end,

sleeves extending into said chambers respectively and sealing the ends of the same, where they communicate with each other, against the escape of the pressure-fluid, plungers fitting fluid-tight within the respective chambers and around the respective sleeves, and rods extending within the sleeves and engaged with the respective plungers.

10. In a mechanism of the type described, the combination with a casing adapted for attachment to an elevator and having a plurality of pressure-fluid chambers therein communicating with each other, sleeves extending downwardly into said chambers respectively and sealing the upper ends of the same against the escape of the pressure-fluid, plungers fitting fluid-tight within the respective chambers and around the respective sleeves, and rods extending within the sleeves and engaged at their lower ends with the respective plungers, said rods adapted at their upper end for connection with suspension cables.

11. A suspension device for connecting an elevator car to hoisting cables, said device comprising a casing attached to the car and having a plurality of pressure-fluid chambers therein communicating with each other, sleeves extending within the said chambers respectively and sealing the same against the escape of pressure-fluid at one end, plungers fitting fluid-tight within the chambers and around the sleeves, and rods extending within the sleeves and engaged with the plungers, respectively, and connected to the suspension cables.

12. In a mechanism of the type described, the combination with a casing provided with a plurality of pressure chambers communicating with each other, pressure plungers sliding in the respective chambers and adapted for independent movement therein; and a pressure-fluid medium confined in the pressure chambers and acted on by the plungers, said medium consisting of a substance which does not become fluid and run at temperatures below 95° F. or thereabout, but is flowable from one chamber to another by the pressure of the plungers.

13. A suspension device for connecting an elevator car to hoisting cables, said device comprising a casing attached to the car and having a plurality of pressure-fluid chambers therein communicating with each other, plungers sliding in the respective chambers and connected with the suspension cables, and paraffin confined in the respective chambers and acted on by the plungers and acting to distribute the weight of the car equally on the plungers.

In testimony whereof, I have affixed my signature hereto.

WILFORD JUDSON HAWKINS.
